UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

RECEPTACLE FOR DRINKING-CUPS.

1,291,245.

Specification of Letters Patent. Patented Jan. 14, 1919.

Application filed April 8, 1916. Serial No. 89,946.

To all whom it may concern:

Be it known that I, WILLARD E. SWIFT, a citizen of the United States, residing at Worcester, in the county of Worcester and

5 Commonwealth of Massachusetts, have invented a new and useful Improvement in Receptacles for Drinking-Cups, of which the following, together with the accompanying drawings, is a specification.

10 The present invention relates to a receptacle for collapsed or folded drinking cups, and is designed to inclose a stack of such cups in the form of a package for insertion within a permanent dispensing or distributing cabinet.

An object of the invention is to provide means for facilitating the charging of such a cabinet with a stack of such cups, whereby the cups are disposed in proper position 20 for withdrawal through the delivery opening of the cabinet, and a further object is to provide means, when the receptacle and inclosed stack have been inserted in the cabinet, for freeing the cups from the receptacle in order to enable them to be independently withdrawn from the cabinet. The invention resides in the provision of a receptacle which affords a temporary closure at the end corresponding to the delivery end 25 of the dispensing cabinet, so arranged that when the receptacle and stack are inserted in the cabinet, the temporarily closed end will be exposed. Thus exposed, it may be rendered inoperative, in order to effect the 30 position of the stack in operative relation to the cabinet, by the withdrawal of said receptacle in the manner hereinafter described.

The invention is fully set forth and described in the following description and illustrated in the accompanying drawings, in which—

Figure 1 is a perspective view of the receptacle, ready for insertion in a distributing cabinet, after having been filled with a stack of cups.

Fig. 2 is a perspective view of the receptacle in an open position, illustrating the construction thereof.

50 Fig. 3 is a vertical sectional view of a distributing or dispensing cabinet, showing a loaded cup receptacle in the act of insertion therein.

Fig. 4 is a vertical sectional view of a distributing or dispensing cabinet, loaded with

cups and ready for use, after the removal of the receptacle shown in Fig. 1.

Similar reference characters refer to similar parts in the different views.

The receptacle or carton which I have 60 chosen to illustrate my invention consists of a box preferably rectangular in cross section and made of cardboard or any other suitable material. Said box provides a bottom 1, sides 2 and 3, and a closed upper end 65 4. At the opposite end of the box the sides 2 and 3 are beveled or chamfered, as indicated at 5, 5, for a purpose hereinafter set forth. The top of the box is preferably formed in two sections 6, 7, the one, 6, being 70 suitably hinged to the side 2, and the other, 7, being suitably hinged to the side 3. When the top is closed, tongues 8, 8 on the section 6 are adapted to interlock in slits 9, 9 of the section 7 in order to retain 75 the parts securely in position. The section 7 of the top has hinged at its lower end a flap 10, which is of sufficient size to close the lower end of the receptacle when the top sections are interlocked together, as shown 80 in Fig. 1. In this position the flap 10 constitutes a closure for the lower end of the receptacle and preferably lies in a plane substantially parallel to the beveled lower edges 5, 5 of the sides 2, 3, said sides projecting beyond the plane occupied by said flap. A string or cord 11, suitably secured to the back side of bottom 1 by means of a pasted tab 12, or the like, is provided for 85 co-operation with a button 13 on the outer 90 face of flap 10, the twisting of the string 11 around the shank of button 13, in the manner common to the fastening of a well known type of merchandise envelop, retains said flap 10 in position, when the receptacle 95 is closed, and enables it to support a stack of cups within the receptacle, as shown in Fig. 3.

As herein shown, the receptacle is designed for use with a dispensing cabinet of the general construction set forth and described in Letters Patent No. 1,151,064, issued August 24, 1915, to Willard E. Swift, in which the cups of the stack each occupy an inclined position within the cabinet, for broadside 100 withdrawal therefrom. For this purpose, I have shown the receptacle having a less cross sectional area than the area of one of the cups, but it is to be understood that my invention is not limited to this construction, 105 110

it being clear that the same is adopted only to satisfy the requirements of the particular type of cabinet herein illustrated and described.

5 When the receptacle has been filled with drinking cups, which are stacked in the manner shown in Fig. 3, the end flap 10 is closed, by twisting the string 11 around the shank of button 13, as shown in Fig. 1. With a
10 stack of cups thus held therein, the receptacle in an upright position is inserted in a cabinet 14, which is provided at its lower end with hinged spring doors 15, 16, as fully set forth in the aforesaid Letters Patent,
15 said doors being provided across the lower inclined bottom of said cabinet. An opening 17 is afforded by these doors when they are in closed position to permit seizure of the lowermost cup of the stack carried within the
20 cabinet. When the package of cups, in the form of the closed stack supporting receptacle, is inserted in the cabinet, the string 11 is exposed to view through the opening 17. In this position the operator is able to reach said string and release it from the button 13, thus allowing the flap 10 to drop downwardly under the weight of the stack of cups. Thereupon the receptacle may be
25 withdrawn from the upper end of the cabinet; the flap 10, being free, assumes a position in the plane of the top 6, 7 as this upward movement of the receptacle proceeds, the stack of cups being thus released and
30 left in the cabinet in properly stacked position, as shown in Fig. 4.

35 The invention enables a complete supply of drinking cups for the cabinet to be inserted by a single operation, and further

insures the proper disposition of the cups within the cabinet in an inclined position, 40 resting on the hinged doors 15, 16. The loading of the receptacle is easily accomplished on account of the ready access to the interior thereof, and the loading of the cabinet by means of the package constituted by 45 such receptacle insures proper stacking of the cups therein, thereby preventing and avoiding inaccurate stacking, which might arise from the carelessness of the operator in case the cabinet were filled direct. 50

The extensions of the beveled sides 2, 3 beyond the plane occupied by the bottom flap 10 of the package effectually prevent displacement of the lowermost cup of the stack, and also serve to guide the stack into 55 proper position in the dispensing cabinet, as the receptacle is being withdrawn therefrom.

I claim:

A receptacle for a stack of collapsed drinking cups, rectangular in cross section and 60 comprising a bottom, sides and a top of less length than the bottom, said top having a flap fitting between the sides of the receptacle, but of greater width than the space between the top and bottom of the box, and 65 means for attaching said flap to the bottom of the box forming a closure for one end of the receptacle, and an inclined support for the stack of cups when the receptacle is placed on end.

Dated this seventh day of April, 1916.

WILLARD E. SWIFT.
